UNITED STATES PATENT OFFICE.

THOMAS J. FEGLY AND GEORGE O. LEOPOLD, OF PHILADELPHIA, PENNSYLVANIA,
ASSIGNORS TO NORTH BRO'S. M'F'G. CO., OF PHILADELPHIA, PENNSYLVANIA, A
CORPORATION OF PENNSYLVANIA.

VISE.

1,268,559.

Specification of Letters Patent.

Patented June 4, 1918.

Application filed July 28, 1917. Serial No. 183,287.

To all whom it may concern:

Be it known that we, THOMAS J. FEGLY and GEORGE O. LEOPOLD, citizens of the United States, and residents of Philadelphia, county of Philadelphia, State of Pennsylvania, have invented certain Improvements in Vises, of which the following is a specification.

Our invention relates to certain improvements in vises of the type known as "universal vises," *i. e.*, capable of being secured to a bench and moved to different positions and secured in the position to which they are adjusted.

One object of our invention is to design a vise of this type so that the parts can be accurately and cheaply manufactured and which will retain the body portion of the vise in any position to which it is adjusted.

A further object of the invention is to provide a single wrench carried by the vise and applicable either to the mechanism for holding the device horizontally, or for holding it against rotary motion.

The invention also relates to details which will be fully described hereinafter, reference being had to the accompanying drawings, in which:

Figure 1 is a side view of a vise illustrating our invention;

Fig. 2 is a sectional view on the line 2—2, Fig. 1;

Fig. 3 is a detached perspective view of the adjustable carrier;

Fig. 4 is a plan view showing the wrench applied to the lower head, the section being taken on the line 4—4, Fig. 1;

Fig. 5 is a detached perspective view of the screw bolt for holding the body portion to the carrier; and

Fig. 6 is a perspective view showing the tubular bolt for holding the carrier to the base.

Referring to the drawings, 2 is a base preferably secured to a bench in any suitable manner by hooks, or other fastenings, and projecting from the base are two uprights 3 having cylindrical openings therein for the reception of a round bar 4, which forms a trunnion for a carrier 5. This bar is rigidly secured to the uprights by pins 6, clearly shown in dotted lines in Figs. 1 and 2. The carrier 5 is made as shown in Fig. 3 and has two jaws 7 and 8 spaced apart

and arranged to be drawn together by a bolt 55 so as to cause the carrier to be clamped firmly to the bar 4 after it is adjusted in a given position.

Mounted on the carrier is the body portion 9 of the vise, which carries the jaw 60 members. The opening in the jaw 7 of the carrier is screw-threaded and the opening in the jaw 8 is plain. A tubular bolt 10 extends through the plain opening and is adapted to the threads of the opening in 65 the jaw 7 of the carrier. On the lower end of this bolt is a hexagonal head 11, in the present instance, and above this head is a flange 12 adapted to a recess in the jaw 8 of the carrier. On turning the bolt in one direction, the jaws of carrier are drawn toward each other so as to clamp the carrier firmly to the bar, and, on the reverse movement, the jaws are separated.

Extending through the tubular bolt is a 75 bolt 13 having a shoulder 14 bearing against a hardened washer 24 at the reduced portion of the jaw 7 of the carrier 5, and on the reduced portion 15 of the bolt is a screw thread adapted to a threaded opening in a 80 nut 16 having a tapered periphery adapted to a tapered opening 17 in the body 9. The nut 16 has an elongated extension 18 adapted to an opening 19 in the upper portion of the carrier 5, as shown in Fig. 3, so that 85 the nut will not turn independently of the carrier when the body portion is turned. The lower end of the bolt 13 is enlarged, as at 20, and on this extension is a hexagonal head 21 of the same size as the head 11 of 90 the bolt 10. 22 is a flange on the head, which prevents the wrench 23 from being disengaged from the bolt 20. The wrench 23 has a hexagonal opening which is adapted either to the head 11 or to the head 21. 95 The reduced portion 20 of the bolt allows for the free movement of the wrench into either of the two positions.

By the construction, as above described, the carrier can be turned on the bar so that 100 the device will assume any position desired, and the body portion 9 can be turned horizontally on the carrier so that it will assume any position desired. The two parts can be locked on turning the two screws by the 105 single wrench 23.

Mounted on the body portion 9 is the vise proper consisting of a fixed jaw 25 and

a movable jaw 26. This movable jaw has a base 27 adapted to rest on the body 9 and has an extension 28 through which passes the clamping screw 29, provided at one end 5 with a loosely mounted bar 30 by which it is turned. This screw 29 is attached to the fixed jaw 25 so that on turning the screw the jaw 26 is moved toward or from the jaw 25. This jaw 25 is held to the body portion 10 9, as shown by dotted lines in Fig. 1. This construction forms no part of the present invention.

We claim:

1. The combination in a vise, of a base 15 having uprights spaced apart; a transverse bar secured to the uprights; a split carrier mounted on the bar; means engaging the two parts of the carrier for clamping it to the bar; a vertical bolt mounted on the carrier; a body portion adjustably clamped to the bolt so as to turn on the carrier; and vise jaws mounted on the body portion.
2. The combination in a vise, of a base 20 having uprights spaced apart; a transverse bar secured to the uprights; a split carrier having two jaws; and means for engaging both jaws so as to draw the clamp tightly to the bar.
3. The combination of a base; a bar secured to the base; a carrier adapted to the bar and having two jaws spaced apart; a hollow screw adapted to turn against one jaw and engage the thread in an opening in the other jaw; a body portion mounted on 35 the carrier; a nut mounted in the body portion and connected to the carrier so that it will be fixed in relation thereto; and a bolt extending through the hollow screw bolt and engaging the nut, said bolt having a shoulder engaging the carrier so that on turning the nut the body portion will be securely locked to the carrier.
4. The combination of a base; two uprights spaced apart; a round bar secured to the uprights; a carrier having a portion engaging the bar and having two jaws spaced apart; a screw for drawing the jaws together so as to clamp the carrier to the bar; a body portion mounted on the carrier; a screw for confining the body portion to the carrier, each of said screws having the same sized heads; and a handle having a wrench adapted to fit the heads and loosely arranged on said last mentioned screw so that the wrench can be shifted to either head in order to operate either screw.
5. The combination of a base; a round bar secured to the base; a carrier mounted on the bar and having two jaws; a tubular bolt extending through one jaw and into the threaded opening in the other jaw; a head one the lower portion of the bolt; a body portion mounted on the carrier; a tapered nut adapted to a tapered opening in the body portion and having a projection adapted to a recess in the carrier so that the nut will be held from turning on the carrier; a bolt extending through the tubular bolt and having a portion adapted to the nut and having a shoulder; the two bolts having 70 heads; and a handle having a wrench portion adapted to fit the heads and loosely arranged on said last mentioned screw so that the wrench can be shifted to either head in order to operate either screw.

In witness whereof we affix our signatures.

THOMAS J. FEGLY.
GEORGE O. LEOPOLD.
